EXTENSION SHELF FOR A LADDER
Adrian Herbert Conner, 13341 Cypress St.,
Garden Grove, Calif.
Filed June 15, 1962, Ser. No. 202,772
1 Claim. (Cl. 248—210)

The present invention relates to step ladders and extension ladders generally and in particular to an extension shelf for a ladder such as a step ladder or extension ladder.

An object of the present invention is to provide an extension shelf for use with either a step ladder or an extension ladder, one which is simple in structure and sturdy of construction, one which may be manufactured in such sizes and from such materials as is most economical, and one which is highly effective in action.

Another object of the present invention is to provide an extension shelf for a ladder which is suitable for either holding a paint pail or container or for holding a paint roller tray, and one which has means for supporting a brush when used with either the paint pail or the roller tray.

A further object of the present invention is to provide an extension shelf for a ladder which may be assembled and disassembled with ease and facility, and one which has special means for adapting it for use on either an extension ladder or a step ladder.

These and other objects and advantages of the present invention will be fully apparent from the following description when taken in connection with the annexed drawing, in which:

FIGURE 1 is a perspective view of a portion of a step ladder showing the shelf of the present invention installed thereon.

FIGURE 2 is a view taken on the line 2—2 of FIGURE 1,

FIGURE 3 is a view taken on the line 3—3 of FIGURE 1 showing in dotted lines a paint roller tray and roller supported upon the shelf.

FIGURE 4 is a view similar to FIGURE 3 showing a paint pail and brush supported upon the shelf.

FIGURE 5 is a view showing the partial detachment of the clamp element which serves to hold the shelf to a ladder.

FIGURE 6 is a view taken on the line 6—6 of FIGURE 1, and

FIGURE 7 is a view similar to FIGURE 2 but showing the means of attaching the shelf to the rail of an extension ladder.

Referring in detail to the drawing in which like numerals indicate like parts throughout the several views, the step ladder is shown in FIGURE 1 and is designated generally by the reference numeral 10. The step ladder 10 has a side rail 12 and rungs 14. The step ladder 10 includes a back leg 16 and a brace 18.

The extension shelf of the present invention is designated generally by the reference numeral 20 and it includes a pair of horizontally disposed support members 22 and 24 arranged in parallel spaced relation. Each of the support members 22 and 24 are provided with sets of grooves 26 and 28 and sets of grooves 30 and 32, respectively.

The groove 26 of the member 22 is in registry with and on the same plane as the groove 30 of the member 24, and similarly, the groove 28 of the member 22 is on the same plane and is in registry with the groove 32 of the member 24. The faces of the member 22 and member 24 having the grooves face each other.

Means is provided for securing the members 22 and 24 together and this means consists in a pair of dowel pins

2

34 and 36 suitably anchored in holes provided in the members 22 and 24.

A single plate element 38 is provided by the present invention and its side edges are slidably received into either the grooves 26 and 30 or the grooves 28 and 34, as shown in FIGURES 3 and 4.

Means is provided on the one element 24 for securing the element 24 to the rail 12. This means consists in a clamping bar member 40 formed of sections 42 and 44 disposed in spaced relation with respect to the one support member 24 and a pair of spaced wing nut and bolt assemblies 46 extending through the bar member 40 and through the support member 24.

In use, the shelf 20 may be either employed with the step ladder 10 or with an extension ladder 10' as in FIGURE 7. In FIGURE 2 the clamping bar member sections 42 and 44 are disposed exteriorly of the rail 12 and in FIGURE 7 the section 44 is shifted to the position between the rail 12' and the support member 24.

It will be seen that the tapered section 44 is complementary to the taper of the outer face of the support member 24 in FIGURE 7.

In FIGURE 3 it will be seen that the plate element 38 has been shifted to the lowermost grooves 28 and 32 and a roller tray 48 is installed with its leg 50 hooked under the dowel pins 34 and 36.

In FIGURE 4 it will be seen that the plate element 38 is inserted in the uppermost grooves 26 and 30 and a paint can or pail 54 rests upon the portion of the element 38 above the dowel pins 34 and 36.

In each of the views of FIGURE 3 and FIGURE 4 the extending portion of the plate element 38 may be employed to support a brush, as at 56 in FIGURE 4.

In FIGURE 5 it will be seen that the sections 42 and 44 of the bar member 40 are notched at one end so that they may be easily swung to an upwardly sloping position away from the rear wing nut and bolt assembly 46 for easy attachment to the ladder rail.

It will be seen that novelty resides in the provisions of the sections 42 and 44 and in the provision of the dowel pins 34 and 36 for supporting the tray 48. Novelty also resides in the two grooves or two sets of grooves in each support member whereby the plate element 38 may be shifted to one of two positions for the purposes above noted.

While only a preferred embodiment of the present invention has been shown and described other embodiments are contemplated and numerous changes and modifications may be made in the invention without departing from the spirit of the invention as set forth in the appended claim.

What is claimed is:

An extension shelf for a ladder comprising a pair of horizontally disposed support members arranged in parallel spaced relation, each of said support members having a pair of spaced longitudinally extending parallel grooves in one face thereof, said members being disposed so that the grooves of one member are in facing relation with respect to the grooves of the other member, said grooves of one member being in registry with the grooves of the other member, a plate element having spaced opposed side walls extending from one end and terminating at points substantially mid-length of said element, the portion of said plate element adjacent the other end being insertable into and withdrawable from either of the sets of registering grooves, said plate element other end portion upon being inserted in one set of grooves forming a support for a paint container, said side walls when said plate element other end portion is inserted in either set of grooves being in end to end registering relation with respect to said support members, means interposed between the sets of grooves securing said members together,

and clamp means connected to the other face of one of said members for attaching said one member to the rail of a ladder, said last named means including a clamping bar member disposed in spaced relation with respect to said one support member and a pair of spaced wing nut and bolt assemblies extending through said bar member and through said one support member.
